Primary Examiner — Adir Aronovich(74) *Attorney, Agent, or Firm* — Rader, Fishman & Grauer PLLC**CLAIM**

The ornamental design for a camera, as shown and described.

DESCRIPTION

FIG. 1 is a front perspective view of a camera showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof.

FIG. 7 is a front perspective view of another embodiment shown with a different environmental structure;

FIG. 8 is a front elevational view thereof;

FIG. 9 is a rear elevational view thereof;

FIG. 10 is a left side elevational view thereof;

FIG. 11 is a right side elevational view thereof; and,

FIG. 12 is a top plan view thereof.

The broken line portions in FIGS. 1-12 are shown to illustrate environment only and form no part of the claimed design.
